PASQUALE IUDICIANI, OF COLUMBUS, OHIO.

SHADE-SUPPORT.

1,109,925.

Specification of Letters Patent.

Patented Sept. 8, 1914.

Application filed March 31, 1914. Serial No. 828,594.

To all whom it may concern:

Be it known that I, PASQUALE IUDICIANI, a citizen of Italy, residing at Columbus, in the county of Franklin and State of Ohio, have invented a new and useful Shade-Support for Window-Frames, of which the following is a specification.

This invention relates to adjustable shade supports and is directed primarily to the provision of a supporting structure for window shades wherein the shade roller may be adjusted to any desired position upon the window frame and maintained in such position. The improvement constitutes an endeavor to produce an efficient adjustable shade support comprised of a minimum number of parts and capable of construction and application at a low cost. At the same time our aim has been to produce a structure, which, notwithstanding its inherent simplicity, is effective and certain of operation.

The features of improvement will appear as this description progresses and attention will be directed to the various figures of the drawing by reference to numerals designating corresponding parts throughout the different figures.

Figure 1, is an elevation of a window frame and the improvement applying thereto. Fig. 2, is a section taken on line 2—2 of Fig. 1. Fig. 3, is a section taken on line 3—3 of Fig. 2. Fig. 4, is a detail and elevation of one of the adjustable shade brackets. Fig. 5, is a detail and elevation of the complementary shade bracket. Fig. 6, is a detail and elevation showing one of the brackets which support the slide rods of the improvement, and Fig. 7, is a detail and section of the structure shown in Fig. 6.

In drawings, the improvement is shown as comprised in part of slide rods, 1 and 2. These slide rods are desirably formed in one continuous piece, being joined at their upper ends 3 so as to form an inverted U. Adjacent to the upper and lower ends they are shown supported by bracket members 4 and 5, preferably stamped from a single piece of sheet metal and bent to embrace spaced rods by means of spaced loops 6 and 7, and intermediate web 8, through which is passed a bolt 9 threaded for the reception of a nut 10. This structure is shown best in Fig. 7 and it will be noted by reference

thereto that loop 7 is extended to form abutting L-shaped feet 11 and 12, which may be secured to the window frame by screws 13. The result is a simple supporting bracket structure formed from a single piece of metal and yet amply rigid to maintain the slide rods firmly in the desired position.

Mounted upon each part of the slide rods is an embracing strip of metal designated 14 and 15 respectively and comprising the central body portion with a U shaped extension 16, curved about the slide rods. Likewise forming an extension of the body portion is a lip 17, perforated at 18, for the reception of a controlling cord 19. In Fig. 4, the body portion of member 14 is provided with a bayonet slot 20, while in Fig. 5, the body portion is provided with a key slot 21. These members 14 and 15 are raised or lowered under the control of the cords 19, which are preferably joined together at their ends and which pass over pulleys 22—23, journaled upon pins as at 24; these pins passing between and through slide rods at their upper ends.

The joined ends of the cords may be secured in any adjusted position by means of disk like cleats, 25. In operation it will be understood that the releasing of the cords 19 from the cleat and a pulling upon the same will cause elevation of the shade roller and that when any desired position by adjustment is attained the cords may again be wound about the cleat and the shade roller is firmly held in adjusted position.

The shade roller may vary as to form but it is desirable to have one end thereof provided with a multiple headed pin as at 26.

It will be apparent that the structure outlined is simple and readily manufactured and that the peculiar manner of mounting the pulleys and of mounting the adjustable shade roller supports, as well as the particular form of supporting brackets and the one piece slide rods, result in a structure readily assembled and cheap to construct. Furthermore, the shade brackets, while being freely slideable are firmly maintained against accidental turning or binding.

What I claim is,

1. An adjustable shade roller support comprising a U-shaped slide rod, a pulley mounted in the upper end of said slide rod, an adjustable shade bracket slideable upon

said slide rod, brackets for supporting said slide rod, and means for control of said shade bracket.

2. An adjustable shade roller support comprising spaced slide rods, adjustable shade bracket controlling mechanism, and a shade bracket comprising a sheet metal piece bent to provide hooks upon both extremities to

embrace the slide rods and having a central extension bent to location between said slide rods.

PASQUALE IUDICIANI.
